UNITED STATES PATENT OFFICE.

AUGUSTUS J. EAVES, OF OSSINING, NEW YORK, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed April 21, 1923. Serial No. 633,629.

To all whom it may concern:

Be it known that I, AUGUSTUS J. EAVES, a citizen of United States, residing at Ossining, in the county of Westchester, State of New York, have invented certain new and useful Improvements in Electromagnetic Devices, of which the following is a full, clear, concise, and exact description.

This invention relates to electromagnetic devices and particularly to polarized telegraph sounders.

An object of the invention is the provision of a new and improved form of polarized sounder which has few and simple parts and which is reliable and efficient in operation.

In accordance with the preferred form of the invention, a simple and efficient means is provided for insuring the maintenance of a uniform high reluctance path between a permanent magnet and the core of an electromagnet.

Referring now to the drawings, Fig. 1 is a side elevation of the invention in its preferred form. Fig. 2 is an end view of the structure of Fig. 1.

In accordance with the showing in the drawing, the polarized sounder comprises a base 7 on which there is mounted a plate 8 which is attached to the base 7 by means of screws 9-9. Mounted on the plate 8 is a pair of electromagnets 10-10. Each of these electromagnets is provided with a soft iron core 12 having its lower ends formed in the shape of pole-pieces 13-13. Suitable screws are provided for clamping the pole-pieces and the electromagnets to the plate 8.

Also mounted on the plate 8 is trunnion yoke 14 carrying a trunnion 15 supporting a sounding bar 19. Carried by the top of the trunnion yoke 14 is a projection having at its free end an aperture in which an adjusting screw 17 is threaded. To the adjusting screw 17 and fitted in a notch in the sounding bar 19, is a balancing spring 18 which serves to balance the movement of the sounding bar 19 with respect to the associated permanent magnet. Intermediate the ends of the sounding bar 19 and just above the cores 12 of the electromagnet 10-10 is fixed to the sounding bar 19 an armature 20, which is attracted due to the magnetization induced in the cores upon the passage of a current through the windings of the electromagnets which have their ends connected to

terminals 11-11. Also carried by the sounding bar 19 is an adjustable screw 21 which is provided with a lock nut for limiting the downward travel of the sounding bar 19.

Also secured to the plate 8 is an anvil 22 which, like the sounding bar 19, is provided with an adjustable screw 23 with a lock nut for limiting the upward travel of the sounding bar 19.

The cores of the electromagnet are polarized by means of a permanent L-shaped magnet 24. The magnet 24 is mounted just above the pole-pieces 13 and has interposed therebetween a spacer 25 which in the preferred form of the invention is of non-magnetic material such as brass. The permanent magnet 24 is secured to the pole-pieces 13 by means of non-magnetic screws 26. The thickness of the spacer 25 varies with the operating current of the circuit over which it is desired to operate the sounder and the strength of the permanent magnet. It has been found that for a current of substantially 6 mils the thickness of this spacer should be approximately $\frac{1}{16}$ ". For other operating currents the thickness of the spacer 25 will of course vary. The provision of a spacer 25 and the manner of mounting the permanent magnet 24 insures the maintenance of a uniform high reluctance path between the permanent magnet and the pole-pieces 13 which is essential in the satisfactory and efficient operation of such devices. It is also to be noted that the mounting of the permanent magnet 24 in the manner just described not only insures a uniform high reluctance path between the permanent magnet and the pole-pieces, but also increases the resonant mass of the sounder. Such an arrangement improves the quality and the clearness of the tones emitted upon the operation of the sounder.

The invention claimed is:

1. In a polarized sounder, a base, an electromagnet carried by said base having cores with pole-pieces secured thereto, a permanent magnet secured to the pole-pieces, and a non-magnetic spacer interposed between said permanent magnet and pole-pieces for maintaining a uniform high reluctance path between it and the pole-pieces of the electromagnet.

2. A polarized sounder, comprising a base, an electromagnet mounted thereon having

cores with pole-pieces secured thereto, a permanent magnet rigidly secured to said pole-pieces, and a brass spacer interposed between said permanent magnet and said pole-pieces for insuring a uniform high reluctance path between it and the cores of the electro-
5 magnet.

3. A polarized sounder, comprising a base, an electromagnet mounted thereon having a
10 core with pole-pieces, an L-shaped perma-

nent magnet rigidly secured to said pole-pieces, and a strip of non-magnetic material interposed between said permanent magnet and said pole-pieces for insuring a uniform high reluctance path between it and the cores 15 of the electromagnet.

In witness whereof, I hereunto subscribe my name this 19 day of April, A. D. 1923.

AUGUSTUS J. EAVES.
